ASSIGNORS TO TOBACCO STEMMING MACHINE COMPANY, OF LYNCHBURG, VIR-
GINIA, A CORPORATION OF DELAWARE.

TOBACCO HANDLING AND STEMMING MACHINE AND METHOD.

Application filed August 11, 1925 Serial No. 49,526.

Our invention relates to a novel method of stemming leaf tobacco which is of especial utility when it is desired to utilize a large part of the stem as well as all of the membrane, and to mechanism for performing the method or process rapidly and economically; also to novel methods and means for handling or feeding leaf tobacco, including a method and means for adjusting and forwarding a group of leaves as a first step in the main process or a first part of the stemming mechanism proper; and an additional method and means for arranging and advancing the leaves to the initial feed mechanism of the main machine. The last named method and mechanism may be used in connection with the main machine, or may be dispensed with as desired; and it also has features of novelty and utility which render it adaptable for other leaf arranging and feeding purposes.

The stemming method proper comprises, as briefly described, advancing the leaf lengthwise and tip-foremost, applying suitable stripping instrumentalities at an intermediate longitudinal point well removed from the tip and usually substantially more than half the total length of the leaf from tip to butt, and removing the membrane at both sides of the stem from that point back to the butt, and then severing the stem substantially at the stripping point or line just above referred to. By operating upon the leaf in this manner the forward part may be properly supported and positive gripping means may be applied to the leaf substantially at or just forward of the stripping line, and the stripping instrumentalities may then act to remove all the membrane to the rear of the stripping line very cleanly from the heavy part of the stem and without any injury to the forward part of the leaf which retains the thinner part of the stem integral with the leaf, for utilization along with the forward part of the membrane in those classes of manufactured tobacco in which stem portions of moderate thickness are not objectionable. The rear membrane portions which have been stripped from the stem are added to the forward portions consisting of the smaller section of stem with its integral membrane; and the heavy rear or butt portions of the stem which have been severed, are handled separately and utilized in any desired way. The

invention also includes mechanism for carrying out this principal part of the method, as sufficiently explained in detail hereafter. 55

Instead of forwarding the leaves singly, a bunch of leaves is usually spread out laterally in separate or partly overlapped arrangement 60 and forwarded at once, and the stripping and stem cutting operations are performed simultaneously on this group. In connection with the main operations, the invention includes the method, as briefly described, of spreading 65 or arranging a group or hand of leaves with their tips directed toward the main machine, and properly adjusting all the leaves by alignment of the butt ends of the stems so that all the leaves are properly positioned 70 for gripping, stripping and stem cutting, and then forwarding the leaves as so arranged to the supporting, gripping and feeding means of the main machine. To carry out this initial or primary leaf arranging and feeding function, the invention also includes suitable mechanism, as sufficiently described in detail hereafter. 75

The invention also includes a novel method 80 of arranging a plurality of bunches or hands of leaves, either in the form of an approximately continuous series of separate leaves, or a continuous layer of more-or-less overlapped leaves, or in substantially separated groups, each of which consists of separate or partially overlapped leaves, and forwarding the leaves in such arrangement laterally to a point where they are delivered for preliminary adjustment and longitudinal movement 85 in the main process and machine. For this preliminary arrangement and handling of the leaves, which may be referred to sometimes for convenience as an auxiliary method, since it may be employed or not, in accordance 90 with operating conditions, the invention includes suitable mechanism, sufficiently described in detail hereafter. 95

In comparison with present methods and machines, the invention provides the desired available output, that is to say, the portions 100 of the whole leaf available for use as manufactured tobacco, including the forward portion of the leaf with the integral stem, identified hereafter as the butted strip, and the rear membrane portions stripped from the heavy part of the stem, hereafter identified 105 as the machine strip, while the severed stems or butts are very cleanly stripped with only

a small percentage of membrane adhering to be removed by thrashing, and this high percent of available output is produced more rapidly and with great economy in labor cost.

The accompanying drawings illustrate mechanism embodying the invention in one form, and also serve to explain an exemplifying performance of the process forming part of the invention. After considering these examples, skilled persons will understand that many variations may be made, both in the machine and method, and we contemplate the employment of any mechanism and processes that are properly within the scope of the appended claims.

Fig. 1 is a vertical, longitudinal section of one suitable mechanism for stemming or stripping tobacco, in accordance with our method as described above and hereafter, including initial leaf arranging and feeding means.

Fig. 2 is a plan view in diagrammatic form of leaf supporting and feeding or conveying means with a leaf positioned therein just after delivery by the initial feeding means.

Fig. 2^A is a vertical section of the same.

Figs. 3 and 3^A, and 4 and 4^A are similar plan and sectional views of the mechanism and leaf at successive subsequent steps of the series of operations.

Fig. 5 is a plan view of the forward or feed end portion of the main machine with the auxiliary or preliminary leaf arranging and feeding mechanism associated therewith.

Fig. 6 is a vertical section at 6—6, Fig. 5.

Fig. 7 is a vertical section at 7—7, Fig. 5, of one suitable initial feed belt driving mechanism.

Fig. 8 is a vertical section at 8—8, Fig. 7.

Fig. 9 is a sectional detail of the intermittent auxiliary feed belt driving mechanism.

The principal part of the machine is built upon or around a frame consisting of longitudinal members 1, with suitable cross members (not particularly shown) and supporting legs 2. This frame supports co-operating upper and lower feed belts 3 and 4 which are driven continuously in the direction indicated by arrows. The lower stretch of the upper belt and the upper stretch of the lower belt run close together to support, grip and advance successive bunches or hands of leaves. Each belt consists of parallel chains 5 running on sprockets 6 secured on the forward shafts 7 and sprockets 8 secured on rear shafts 9. Each belt carries a series of spaced leaf supporting and gripping instrumentalities. Each of these instrumentalities includes a plurality of spaced parallel slats 10 and at the rear of the series of slats (with reference to the direction of active feed movement as indicated in Figs. 2, 2^A and elsewhere) is a gripper bar 11 having a ribbed or serrated gripping face 12 and a curved or approximately arcuate upper or lower sur-

face 13 leading to a thin rear edge 14. At the feed end of the machine (at the right in Fig. 1) as the belts converge around the upper and lower sprockets 6, the leading slats 10 of the successive upper and lower supporting and gripping instrumentalities come together in vertically aligned relation and subsequently the corresponding members of the complete pair of supporting and gripping instrumentalities are vertically aligned and proceed as a unit, as clearly indicated in Figs. 2, 2^A, 3, 3^A, 4 and 4^A, to the rear end of the machine, where the belts and supporting and gripping instrumentalities travel around the rear sprockets 8, and so back to the feed end of the machine. The supporting and gripping units on each belt are spaced apart a substantial distance, these being calculated with reference to the required time for properly arranging and advancing the successive groups of leaves so that a group may be advanced at the proper time for reception by each supporting and gripping unit as its upper and lower sections pass about the forward sprockets 6.

The length of the series of slats of one of the supporting and gripping instrumentalities and the associated gripper bar is calculated with reference to the distance from the point X of the leaf L, Fig. 1 (which is the point at which the stem is subsequently to be severed) and the tip T of substantially the longest leaves of the class of tobacco which is to be handled. The leaf part consisting of membrane and integral stem designated as C, forward of the point or transverse line X, called the butted strip, has a length dependent on the average thickness of the stem contained in that part; that is to say, it is usually desired to make the butted strip as long as possible without including in it very thick stem portions. Therefore the cutting point or line X to the rear of which the leaf membrane sections D, hereafter designated as machine strip, are to be removed, is located as far from the tip T as possible. The relative dimensions in Figs. 2, 3, and 4 are fairly representative of average operating conditions. The butted strip C is somewhat more than two-thirds, or nearly three-fourths the total length of the leaf, while the machine strip portions d and the stem butts s, hereafter called the machine stem, since it is severed by machine operations, are, correspondingly, somewhat less than one-third or approximately one-fourth the total length of the leaf. As the leaf is advanced between the advancing belt stretches, the tip portion is lightly held and supported, and fed along by the forward upper and lower slats 10, and successive pairs of slats lightly grip, support and advance successive portions of the leaf part c, and finally a substantial lateral zone of the leaf is firmly gripped between ribbed faces 12 of the upper and lower

gripper bars 11, whose rear edges 14 now define substantially the severing line X, Fig. 2. The forward part or section c of the leaf is thus supported in smooth, flat, horizontal position and when delivered at the delivery end of the belts may be maintained in such position for convenient straight advance or for piling in flat condition for convenient transfer to a tobacco working machine, such as one which requires the leaves including integral stem portions to be cut at right angles to their length, in order that the stem portions retained for use shall be thin cross-sectional slices and not relatively long slivers, which would be produced by cutting the stems diagonally or approximately lengthwise. The entire rear part of the leaf, back of the line X is free for subsequent action of the stripping and stem cutting instrumentalities.

At a point located to allow proper travel of one supporting and feeding instrumentality, are upper and lower stripping rolls 20 and 21 having the usual stripping wires. These rolls are driven in any known or suitable way, in the direction of the arrows, and they are carried on pivoted arms 22, 23, respectively, connected to move together in any suitable way, for example, by gear sectors 24. One set of supporting arms, such as 23, carried by the pivot shaft 25, co-operate with another arm 26, which has a cam follower 27 running in a track 28 on a cam body 29, which is driven in any convenient way in such relation to the belt travel that the cam makes one turn for the passage of each set of supporting and gripping instrumentalities 10-11. The cam track is so contoured that as each forward pair of slats 10 approaches the stripping rolls 20 and 21, the latter are retracted upward and downward respectively, permitting the slats and the gripper bars to pass, carrying the forward part of the leaf between the rolls. The cam track then acts to move the rolls quickly downward as the thick forward parts of the gripper bars pass between them, and as the thin rear edges 14 of the bars pass the vertical plane of the stripper axes, the stripping blades bite quickly down into the leaf membrane, substantially at the line X, and strip the machine strip portions d from the stem as the leaf continues to advance. Preferably, the rolls are brought relatively close together when their blades first bite into the leaf to insure proper severing along the line X and then as the leaf advances the rolls are retracted somewhat to reduce the stripping pull and avoid stem breakage, but are kept close enough together to provide the proper clean stripping of the stem. The machine strip portions d are collected in any suitable way, for instance by permitting them to fall into a hopper 30. The cam channel now causes the rolls to be retracted and so held until their next action.

At a convenient distance beyond the strip-

ping rolls, upper and lower cutter blades 35 and 36 are carried by pivoted arms 37 and 38 respectively. These arms are operated simultaneously, for instance, by the pin and jaw connection 40 and by an arm 41 operatively connected to the lower arms 38 and also connected by a link 42 to a cam follower 43 running on a cam 44 carried by a shaft 45. This shaft is driven in step with the feed belts and in accordance with the rate of rotation of cam body 29. As the leaf supporting and advancing instrumentalities pass between the cutter blades, they are retracted upward and downward respectively, and then as the rear edges 14 of the gripper bars pass, the blades are brought quickly together by the action of cam 44 and the stem is cut at the point X, the severed portions or machine stems s falling into a hopper 50. The butted strips c are then delivered at the left as the belts separate and may be collected in a hopper 55 or kept in straight and flat condition, for reasons indicated above, by delivering them upon a table or carry-off belt.

As above stated, the driving connections may vary greatly. Any convenient shaft, such as cam shaft 45, may be the initial driving member of the mechanism, and the belts may be driven by gear or sprocket connections between their shafts 7 or 9 and by gear or sprocket connection from any of the belt shaft, such as lower shaft 9, to the cam shaft 45. The shaft of cam 29 may be driven by a chain from cam shaft 45.

Any convenient table may be located at the right in Fig. 1, for the convenience of the operator in laying out a bunch of leaves, and for pushing them between the feed belts as forward upper and lower slats 10 converge in the vertical plane of shafts 7. The bunch of leaves to be laid out for feeding at one time may consist of one or more hands of leaves, and the leaves may be fully spread so that they are substantially separate, or so that in some cases only the membranous portions of adjacent leaves are overlapped, or otherwise, the leaves may be very considerably overlapped. The machine will operate satisfactorily even when several leaves (two, three or even more) are substantially superposed or with the stems lying very nearly on top of each other. The spread of the leaves may evidently, therefore, be varied in accordance with the nature of the leaf and operating conditions.

It is preferred to provide initial feed mechanism which is at least partly automatic in operation, to facilitate the arrangement of the groups of leaves, to reduce the time required for such arrangement, or at least to so facilitate the arrangement of the leaves so that the machine may be operated at a satisfactorily high rate of speed, and particularly to automatically adjust the leaves in ways and for reasons explained below.

For this purpose an initial feed belt 60 is arranged at the feed end of the machine and supported on forward and rear pulleys 61 and 62. It is natural to refer to the feed end of the machine (at the right in Fig. 1) as the front of the machine. The leaves are, of course, advanced toward the rear or discharge end of the machine and while the movement of the leaves is naturally considered a forward movement in one sense, this direction of leaf movement should not be confused with statements of position with regard to the machine. If necessary, the upper stretch of the belt may be supported on a shelf. Toward the front end of the feed belt, usually substantially above the forward pulley 61, is a vertical stop rail or abutment 63, which may, if desired, be supported in any convenient way for adjustment toward or from the main feed belts 3 and 4. A group of leaves is spread out laterally on the upper stretch of belt 60 with the tips directed toward the main feed belts and the butt ends of the stems pointing toward the stop rail 63 in more or less indiscriminate longitudinal positions. After one of the main supporting and feeding units 10-11 has passed forward between the adjacent stretches of the main feed belts, the bunch of leaves is arranged, in any of the ways above stated, on belt 60, and the upper stretch of the belt is then moved reversely or toward the right in Fig. 1, bringing the butt ends of all the stems against the stop rail 63 and aligning these stems. The tips of different leaves are then in different longitudinal positions depending on the lengths of the respective leaves. The belt 60 is then moved forward (or in the normal feed direction) at the proper time, its movement being calculated so that the tips of the longest leaves are brought into the vertical plane of shafts 7, as the forward slats 10 of the next approaching supporting and feeding unit converge to grip and advance the leaves. Desirably, the belt 60 is driven in the feed direction at a rate substantially faster than the linear speed of the main feed belt. In this way, the shorter leaves are advanced farther with relation to travel of the main belts than the long leaves, and are in turn gripped by successive pairs of slats. There is thus provided an automatic leaf adjustment substantially proportional to the leaf length, so that all of the leaves are gripped by the gripper bars 11, in such a position that the line X for each leaf is automatically positioned for the machine stripping of the correct portion of its membrane d.

Various mechanism may be provided for driving the initial feed belt 60 in the manner described. One preferred mechanism is illustrated in Figs. 1, 7 and 8. A longitudinal shaft 70 is driven in any convenient way from another shaft such as shaft 45, if that is the initial drive shaft of the machine, and by

spiral gears 71 and 72, drives a transverse shaft 73. The total ratio of the gearing from the initial driving point to shaft 73 is such that shaft 73 makes one turn in each cycle of the machine, that is, one turn for the travel of each feed unit 10-11 past a given point. Parallel to shaft 73 is a shaft 75 and this is connected by sprockets 76, 77, and a chain 78 to the shaft 79 of forward belt pulley 61. 70

Adjacent gear 72 another gear 80 is revolvably mounted on the shaft and engages a pinion 81 secured on shaft 75 for driving the latter in one direction. Some distance from gear 80 a sprocket 82 is revolvably mounted on shaft 73, and is connected by a chain 83 80 to a sprocket 84 fixed on shaft 75 for driving the latter in the opposite direction.

A circular ratchet 86 is secured to gear 80 and a similar ratchet 87 is secured to sprocket 82. Between the ratchets, pawl arms 88 and 89 are arranged with their hubs secured together and keyed to shaft 73.

Cams 90 and 91 are secured to a holder 92, the hub of which fits revolvably on the hubs of the arms 88 and 89. The holder has an arm 93, Fig. 7, secured to a stationary point such as a part of a gear box (not shown) in which this gearing may be enclosed. The cams may be adjusted rotatably upon the holder 92 and then secured to it and are held stationary by arm 93. Pawl arm 88 has at its outer end a pivotally mounted pawl 95 to co-operate with the teeth of the circular ratchet 86 and also has a cam follower arm 96, the rounded end of which runs on the periphery of cam 90. The pawl and follower are urged to active position by springs 97 and are connected by means of the pivot pin 98. Pawl arm 89 carries similar mechanism including pawl 100 to co-operate with ratchet 87, cam follower 101 to co-operate with cam 91, and springs 102.

Shaft 73 is continuously driven, clockwise, as viewed in Fig. 7. Cam 91 is contoured so that at the proper time for a rearward (stem end adjustment) movement of feed belt 60, cam follower 101 which is carried by its arm 89 along with shaft 73 strikes a drop on the cam face. Movement of the follower permits pawl 100 to engage its ratchet 87 and sprocket 82 is thus driven along with the shaft and by chain connection to sprocket 84, shaft 75 is also driven clockwise. This motion is transmitted by a belt 78 to the rear pulley 61 of feed belt 60, and the belt is moved backward or to the right in Fig. 1 to adjust the stem ends as previously described. Toward the end of the necessary feed belt movement, follower 101 strikes a rise on the cam face and pulls pawl 100 away from the ratchet, thus breaking the driving connection between shaft 73 and sprocket 80, and belt 60 stops. Immediately thereafter cam follower 96 moving with shaft 73 strikes a drop in the face of cam 90 and pawl 95 125 130

is thus engaged with ratchet 86, coupling gear 80 to shaft 73. The pinion 81 on shaft 75 is thus driven counter-clockwise as viewed in Figs. 1 and 7, and belt 60 is driven forward to feed the leaves as previously described.

The gear ratios and other parts are so designed that preferably belt 60 travels in the feeding direction much faster than the linear speed of the main feed belts 3 and 4. One desired ratio is approximately 2.32. This ratio may be varied greatly, but has been found in one practical embodiment of the invention to give the desired adjusting effect for long and short leaves. The reverse motion speed of the belt is desirably, (although not necessarily) higher than that of the main belts. When the reverse motion is speeded up, considerable time is saved. One desirable speed ratio (which may be greatly varied) as between the feed belt 60 and the main belts 3 and 4 may be approximately 2.64. The total saving of time by rapid driving of the feed belt in both directions, is such that these movements backward and forward require only a small part of the total time of one cycle, and the operator, when hand labor is employed for placing the leaves on the feed belt, therefore has more time for the proper placing and spreading of the leaves.

While the machine may be operated satisfactorily with hand labor for the placing of leaves on the primary feed belt, the machine may be speeded up substantially and labor cost may be saved by providing auxiliary or preliminary feeding mechanisms for supplying the leaves as rapidly as may be desired to the initial feed belt 60. For this purpose an auxiliary belt 200 is arranged to run at a right angle to belt 60. This belt is supported by various pulleys on any suitable frame including side members 201, cross members 202, and legs (not shown). The rear belt pulley 205 is carried by a shaft 206 mounted in fixed bearings and the shaft carries a circular ratchet 207 engaged by a pawl 208 mounted on a fixed frame member to prevent reverse motion of the pulley, which moves intermittently when the belt is moved, as hereafter explained, in the direction of the arrow. A carriage 210 is provided with rollers 211, running in ways 212 in the frame side members 201. This carriage has arms 213 provided with bearings for a shaft 214 on which a forward belt pulley 215 is mounted. The upper stretch of the belt passes around pulley 215 and back horizontally, and then around an idler pulley 216, mounted in fixed bearings in the frame. This pulley or its shaft has a circular ratchet 217 engaged by a pawl 218 to prevent reverse motion of the pulley and the belt at that point. The belt then passes down and around an idler 221 mounted on arms 222 which are pivoted at 223 on fixed frame brackets 224. From pulleys 221 the belt goes around another fixed

idler 225 and then around another fixed idler 226 mounted in the brackets 224, and so up and around rear pulley 205, completing the belt circuit. The movable idler 221 serves to maintain a variable slack in the belt including the belt stretches 230 and 231.

The carriage is moved to and fro by any suitable means, represented in one preferred form by a crank 240 on a vertical shaft 241, which extends from the top of a gear box 242 mounted below the belt and carriage. Shaft 241 is intermittently driven by any suitable connection to the main machine. This connection is represented in the present instance by a bevel gear 243 on the shaft engaged by a pinion 244 on a horizontal shaft 245, sprockets and a chain 246, a countershaft 247, sprockets and a chain 248, from any suitable rotary part of the main machine, for example, shaft 73. The pinion 244 is secured to a hub 244^a which is rotatably mounted on the shaft 245. This hub also carries a circular flange 244^b having a plurality of notches 244^c. In the present instance, for a certain set of driving ratios there are three of these notches. 80 Adjacent the circular flange or disc 244^b another circular flange or disc 244^d is keyed to the shaft. This disc carries a pivoted pawl 244^e, the toe of which is adapted to engage the notches 244^c or to ride between them over the circular periphery of disc 244^b. This pawl is urged to engagement by a spring 244^f. It has a projecting lug or dog 244^g adapted to cooperate with a pin 244^h fixed in a side wall of the gear box.

The described arrangement provides for an advance movement of the auxiliary feed belt (toward the right, in Fig. 6) to deliver one group of leaves to the primary feed belt 60 while the latter is stationary, and for a dwell while belt 60 moves first in reverse direction and then forward to feed the leaves; and for return movement of belt 200 (to the left in Fig. 6) during the next rest period of belt 60 to place another group of leaves thereon, and for a dwell of belt 200 while belt 60 performs its next adjusting and feeding movements, and so on; or in other words, according to the present specific arrangement, belt 200 alternately advances and retreats in its leaf delivering operations. When shaft 245 is driven, as in the present specific arrangement, synchronously with the main machine, or in other words, when it makes one turn for each feed cycle of belt 60, pinion 244 is three-quarters the diameter of gear 243; or specifically, if pinion 244 has eighteen teeth, gear 243 will have twenty-four teeth. Disc 244^d driven continuously by shaft 245, causes pawl 244^e with its toe in one of the notches 244^c to drive disc 244^b and the connected pinion 244 along with the shaft during two-thirds of one shaft rotation. Through crank 240 and pitman 250 the carriage 210 is advanced (toward the right in 100 110 120 125 130

Fig. 6) until just before crank 240 reaches one of its dead center positions, dog 244^g of the pawl strikes the fixed pin 244^h and withdraws the pawl from the notch. Pinion 244, gear 243 with its shaft 241, crank 240, pitman 250, and the carriage then stop, with pulley 215 and the forward part of the belt projected over belt 60, as shown in Fig. 6. The carriage with the projected belt portion then remains stationary during the remaining one-third rotation of shaft 245 while belt 60 performs its leaf adjusting and feeding movements. At this time disc 244^a has turned far enough to carry dog 244^g away from pin 244^h; the pawl while the belt was stationary has ridden over the peripheral segment of disc 244^a and now drops into the next notch 244^b. At this point one cycle of the auxiliary belt driving mechanism is completed. The belt is then driven in the reverse direction (to the left in Fig. 6) and at the end of this reverse or retreating movement the intermittent driving mechanism provides another dwell equivalent to one-third of the total cycle of belt 200, and so on.

While belt 200 is driven by positive engaging members, namely, the pawl 244^e and the notched disc 244^b, there is relatively little shock and strain on these parts because whenever the pawl engages a disc notch to drive the belt, the belt and its carriage are at rest, and the crank 240 and pitman 250 are in dead center position, so that at first the pawl has only the relatively light duty of starting crank 240 and the pitman, with practically no load thereon, and then the carriage is gradually started and rapidly accelerated in either direction by the changing angularity of crank 240, and is then brought gradually to rest at the end of its stroke.

One or more operators place tobacco leaves on belt 200, either while it is moving or stationary; but rests of the belt provide additional time and facility for the operator to properly adjust the leaves without annoyance by belt movement. The leaves are arranged transversely of the belt corresponding to their desired longitudinal arrangement on the initial feed belt 60, as sufficiently indicated in Fig. 5, and the precise arrangement for feeding in the main machine as above described. That is, the leaves may be in the form of a substantially continuous series without overlap or more or less overlapped. Otherwise, if difficulty is experienced in separating successive sets or groups of leaves as they are delivered from the auxiliary belt 200 to the initial feed belt 60, the leaves may be arranged on belt 200 in substantially separated series or groups. For this purpose suitable index marks, such as 300, may be placed on one of the frame side members 201 to indicate the proper spacing of the leaf groups.

When the delivery portion of belt 200

advances (toward the right in Fig. 6) the lower stretches of the belt are prevented from moving reversely by pawl 218 engaging ratchet 217 of pulley 216. The upper or active stretch of the belt therefore moves forward in the direction of the arrow at double the speed of carriage advance, and this movement is permitted by pawl 208 running idly over the teeth of ratchet 207 as pulley 205 rotates in the direction of the arrow. During this movement some of the slack in belt stretches 230 and 231 is taken up with accompanying rise of movable idler pulley 221. As the belt moves forward a group, or a portion of the continuous series of leaves adjacent pulley 215 is moved forward and deposited in reversed position on belt 60. When carriage 210 and belt 200 come to rest this bunch or group of leaves is adjusted and fed forward by belt 60. Then, while belt 60 is again at rest, carriage 210, with the projected portion of belt 200, retreats (toward the left in Fig. 6). During this movement the upper stretch of belt 200 is held stationary by pawl 208 engaging ratchet 207, but the lower stretches of the belt are moved in the direction of the arrow by the weighed idler 221 which takes up the belt slack and also causes the stretch of the belt between pulleys 216 and 215 to be pulled around pulley 215, as the latter retreats. In this way another group or portion of a layer of leaves on belt 200 is dropped off (without reversal of position) upon belt 60; and so on.

The driving arrangement of belt 200 in what may be called half-time relation to the cycle of the main machine, with deposition of leaves on the initial feed belt 60 at each forward and retreating movement, provides substantially for only one-half the total movement of belt 200 that would otherwise be necessary; otherwise, however, the belt can evidently be made to move forward once for each cycle of the main machine and by slight changes in construction or arrangement of the belt operating mechanism can be made to deposit a group of leaves at each movement, in one direction (either as it is advancing or retreating).

Evidently the frame of the auxiliary feed mechanism may be extended to any desired extent so that the upper stretch of the belt may be made as long as is necessary to permit the required number of operators to properly handle the hands of tobacco and spread them properly upon the belt. These requirements will vary with the desired speed of operation and for other reasons.

We claim:—

1. A tobacco stemming machine comprising main belts arranged with parallel stretches, a spaced series of leaf supporting and gripping instrumentalities on each belt, each instrumentality being arranged to cooperate with one on the other belt, means for

advancing a group of leaves tip first and introducing forward portions of the leaves between converging supporting and gripping instrumentalities at the feed end of the feed belts, stripping instrumentalities arranged to engage rearward projecting portions of the leaves and strip the membrane from each side of the stems from approximately the gripping line to the butts, and subsequently acting means for severing the projecting stem portions.

2. A tobacco stemming machine comprising main belts arranged with parallel stretches, a spaced series of leaf supporting and gripping instrumentalities on each belt, each instrumentality being arranged to co-operate with one on the other belt, means for supporting a plurality of leaves in partly overlapped relation, means for aligning the butt ends of the stems, means for then advancing the group of leaves tip first and introducing them between converging supporting and gripping instrumentalities at the feed end of the feed belts, stripping instrumentalities arranged to engage rearward projecting portions of the leaves and strip the membrane from each side of the stems from approximately the gripping line to the butts, and subsequently acting means for severing the projecting stem portions.

3. Tobacco stemming mechanism comprising co-operating continuous feed belts, leaf supporting and gripping means on each belt positioned to come together to receive, support and grip the forward part of a leaf and advance it tip first with the rear part accessible, co-operating strippers, means for moving them to contact with the leaf at the rear of the gripping means and strip the leaf membrane from the leaf and each side of the stem, subsequently acting means for severing the projecting stem portion, an initial feed belt, and means for moving it intermittently to advance successive groups of leaves to the main feed belts.

4. Tobacco stemming mechanism comprising co-operating continuous feed belts, leaf supporting and gripping means on each belt positioned to come together to receive, support and grip the forward part of a leaf and advance it tip first with the rear part accessible, co-operating strippers, means for moving them to contact with the leaf at the rear of the gripping means and strip the leaf membrane from the leaf and each side of the stem, subsequently acting means for severing the projecting stem portion, an initial feed belt to receive successive groups of leaves, a stem adjusting abutment adjacent the belt, and means for moving the belt to adjust the stems and then to feed the leaves to the supporting and gripping instrumentalities of the main feed belts.

5. Tobacco stemming mechanism comprising co-operating continuous feed belts, leaf

supporting and gripping means on each belt positioned to come together to receive, support and grip the forward part of a leaf and advance it tip first with the rear part accessible, co-operating strippers, means for moving them to contact with the leaf at the rear of the gripping means and strip the leaf membrane from the leaf and each side of the stem, subsequently acting means for severing the projecting stem portion, an initial feed belt to receive successive groups of leaves, a stem adjusting abutment near the forward end of the belt, means for moving the belt to adjust the stems against the abutment and then in the opposite direction to feed the leaves to the supporting and gripping instrumentalities of the main feed belts, the last driving means being arranged to move the initial feed belt at substantially higher speed than the main belts, so that the initial feed belt and the supporting and gripping instrumentalities of the main belts co-operate to adjust different leaves of a group longitudinally, approximately in accordance with their relative lengths.

6. Tobacco stemming mechanism comprising co-operating continuous feed belts, leaf supporting and gripping means on each belt positioned to come together to receive, support and grip the forward part of a leaf and advance it tip first with the rear part accessible, co-operating strippers, means for moving them to contact with the leaf at the rear of the gripping means and strip the leaf membrane from the leaf and each side of the stem, subsequently acting means for severing the projecting stem portion, an initial feed belt, means for moving it intermittently to advance successive groups of leaves to the main feed belts, and a preliminary feed belt arranged to move substantially at a right angle to the movement of the initial feed belt and to support a series of leaves and deliver groups of leaves to the initial feed belt.

7. Tobacco stemming mechanism comprising co-operating continuous feed belts, leaf supporting and gripping means on each belt positioned to come together to receive, support and grip the forward part of a leaf and advance it tip first with the rear part accessible, co-operating strippers, means for moving them to contact with the leaf at the rear of the gripping means and strip the leaf membrane from the leaf and each side of the stem, subsequently acting means for severing the projecting stem portion, an initial feed belt, means for moving it intermittently to advance successive groups of leaves to the main feed belts, a preliminary feed belt arranged to move substantially at a right angle to the movement of the initial feed belt and to support a series of leaves and deliver groups of leaves to the initial feed belt, and means for moving the preliminary feed belt intermittently.

8. Tobacco stemming mechanism comprising co-operating continuous feed belts, leaf supporting and gripping means on each belt positioned to come together to receive, support and grip the forward part of a leaf and advance it tip first with the rear part accessible, co-operating strippers, means for moving them to contact with the leaf at the rear of the gripping means and strip the leaf membrane from the leaf and each side of the stem, subsequently acting means for severing the projecting stem portion, an initial feed belt, means for moving it intermittently to advance successive groups of leaves to the main feed belts, a preliminary feed belt arranged to move substantially at a right angle to the movement of the initial feed belt and to support a series of partly overlapped leaves and deliver groups of leaves to the initial feed belt, and means for moving a part of the preliminary feed belt intermittently over and away from the initial feed belt.

9. Preliminary or auxiliary feed mechanism for handling leaf tobacco, comprising a continuous belt, a fixed supporting pulley, a movable supporting pulley, means for moving the movable pulley intermittently to and fro to extend and retract one end of the belt for delivery purposes, and means for maintaining available slack in an idle part of the belt.

10. Preliminary or auxiliary feed mechanism for handling leaf tobacco, comprising a continuous belt, a fixed supporting pulley, a movable supporting pulley, means for moving the movable pulley intermittently to and fro to extend and retract one end of the belt for delivery purposes, means for maintaining available slack in an idle part of the belt, and means preventing the reverse travel of the active stretch of the belt.

11. Preliminary or auxiliary feed mechanism for handling leaf tobacco, comprising a continuous belt, a fixed supporting pulley, a reciprocable carriage, a belt pulley thereon, means for reciprocating the carriage to project and retract a portion of the belt for delivery purposes, means preventing reverse travel of the active stretch of the belt and permitting forward travel, and means for maintaining variable slack in an idle part of the belt.

12. Preliminary feed mechanism for a stripping machine of the class described which includes an initial feed belt, said mechanism comprising a belt arranged to receive a series of tobacco leaves, and means for moving the active stretch of the belt intermittently over and away from said initial feed belt of the main machine.

13. Preliminary feed mechanism for a stripping machine of the class described which includes an initial feed belt, said mechanism comprising a feed belt, means for moving a portion of the belt intermittently to and fro in relation to said initial feed belt of the main machine, and means for simultaneously mov-

ing the active stretch of the feed belt in an advancing direction to deliver leaves carried by it to said initial feed belt of the main machine.

14. A tobacco leaf strip or stemming machine devised for the retention of a large part of the stem from the leaf tip rearward along with the corresponding leaf membrane, for utilization with rearward portions of the membrane removed from the stem, comprising main feeding means arranged to grasp one or more leaves transversely on lines somewhat rearward of the leaf-mid-length, means for operating said main feed means to advance the leaf or leaves longitudinally in a direction parallel to their stems and tip first, stripping means arranged to engage the leaves and sever and strip the rearward parts of the membrane substantially from the grasping line to the butt ends, and means acting thereafter to sever the projecting stems substantially at the grasping line.

15. A tobacco leaf strip or stemming machine device for the retention of a large part of the stem from the leaf tip rearward along with the corresponding leaf membrane, for utilization with rearward portions of the membrane removed from the stem, comprising main feeding means arranged to grasp one or more leaves transversely on lines somewhat rearward of the leaf-mid-length, means for operating said main feed means to advance the leaf or leaves longitudinally in a direction parallel to their stems and tip first, stripping means arranged to engage the leaves and sever and strip the rearward parts of the membrane substantially from the grasping line to the butt ends, means acting thereafter to sever the projecting stems substantially at the grasping line, and initial feed means providing facility for arranging leaves for advance to the main feed means longitudinally and tip first, said initial feed means being operated to advance the leaves faster than the rate of movement of the main feed means, so that the gripping line for each leaf is regulated substantially in accordance with leaf length.

16. A tobacco stemming machine comprising feed belts having adjacent parallel stretches and transverse grippers thereon arranged to converge at the feed end of the belts and grip between them a tobacco leaf near its mid-length and convey the leaf tip-first longitudinally through the machine, complementary stripper rolls arranged at opposite sides of the adjacent belt stretches, and means for moving the rolls divergently to permit passage of the grippers, and convergently to engage the leaf close behind the grippers and strip from the stem the membrane portions back of the grippers, and subsequently acting cutting means to sever the portion of the stem extending behind the grippers.

17. A method of stemming tobacco comprising gripping a leaf transversely near its mid-length, advancing it tip first in the direction of its stem, applying stripping instrumentalities to the membrane close to the gripping line and stripping from the stem the portions of the membrane back of the gripping line, and then severing the stem substantially at the gripping line.
18. The method of stemming tobacco, which consists in stripping the lamina toward the butt from a selected line transverse to the leaf and nearer the butt than the tip, whereby to leave the major portion of the lamina intact, and severing the stripped portion of the stem from the remainder.
19. The method of stemming tobacco, which consists in moving leaves lengthwise and tip first past stripping mechanism arranged to engage the leaf throughout its width and to strip rearwardly toward the
20. The method of stemming tobacco, which consists in grasping the leaf throughout its width on a line transverse to the leaf nearer the butt than the tip, moving the leaf so held, lengthwise and tip first past stripping devices arranged to strip toward the butt, while shielding the portion of the lamina in front of the line on which the leaf is grasped, and afterwards severing the stripped portion of the stem from the remainder.

Signed at Lynchburg, in the county of Campbell and State of Virginia, this 3rd day of August, A. D. 1925.
